(57) **CLAIM**

The ornamental design for a "safety mirror," as shown and described.

DESCRIPTION

FIG. 1 is a perspective view showing the safety mirror of our design;

FIG. 2 is a perspective view of a safety mirror showing our new design;

FIG. 3 is a front view thereof;

FIG. 4 is a rear view thereof;

FIG. 5 is a right side view thereof;

FIG. 6 is a left side view thereof;

FIG. 7 is a top plan view thereof; and,

FIG. 8 is a bottom plan view thereof.

The broken line showing of a vehicle in FIG. 1 forms no part of the claimed design.
